WINDOW VENTILATING MECHANISM

Millard H. Toncray and Earl H. Pickett, Detroit,
Mich., assignors to Hudson Motor Car Company,
Detroit, Mich., a corporation of Michigan

Application September 23, 1933, Serial No. 690,644
Renewed May 7, 1937

5 Claims. (Cl. 296—44)

This invention relates to ventilating windows and is particularly adapted for use in automobile or other closed vehicle bodies. The invention may be embodied in any one or all of the doors 5 of the body or, in the case of a sedan for example, may be used in connection with the rear quarter window.

An object of the invention is to provide a ventilating window structure embodying a glass panel 10 which may be shifted vertically within a window opening in the body to open and close the same and which also may be swung in a horizontal direction about a vertical axis into different adjusted positions, when the panel is in elevated position, to provide a ventilating opening.

Another object of the invention is to provide a vertically slidable glass carrying panel capable of horizontal swinging movement when the panel is in elevated position, and wherein a regulator 20 mechanism having a single operating control is provided for imparting both sliding and swinging movements to the panel.

A further object of the invention is to provide a vehicle body having a window opening adapted 25 to be closed by means of two vertically sliding glass carrying panels, one of said panels having the glass thereof pivoted to swing horizontally when the panel is elevated, and wherein regulator mechanism is provided for independently 30 raising and lowering said panels and also for swinging the pivoted glass when in raised position within the window opening.

Other objects of this invention will appear in the following description and appended claims, 35 reference being had to the accompanying drawings forming a part of this specification wherein like reference characters designate corresponding parts in the several views.

Fig. 1 is an elevation, partly broken away, 40 taken from the inside of an automobile door and illustrating one embodiment of the invention.

Fig. 2 is a similar view on a smaller scale, illustrating the glass panels in lowered positions.

Fig. 3 is an elevation, partly broken away, 45 taken from the outside of the door and illustrating the glass panels in elevated position.

Fig. 4 is a section taken through lines 4—4 of Fig. 1 in the direction of the arrows.

Fig. 5 is a section taken through lines 5—5 of Fig. 1 in the direction of the arrows.

Fig. 6 is a section taken through lines 6—6 of Fig. 1 in the direction of the arrows.

Fig. 7 is a section taken through line 7—7 of Fig. 1 in the direction of the arrows.

Fig. 8 is a section taken through lines 8—8 of Fig. 1 in the direction of the arrows.

Fig. 9 is a fragmentary elevation taken from the outside of the door and showing a modified form of construction.

Fig. 10 is a view similar to Fig. 9 showing one of the glass panels in elevated position and one in lowered position.

Fig. 11 is a horizontal section taken substantially along the line 11—11 of Fig. 9 in the direction of the arrows.

Fig. 12 is a horizontal section taken substantially along the line 12—12 of Fig. 9 in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the present instance the invention has been embodied, by way of example, in the front door of an automobile body although it is understood that the structure may be applied to any window opening in the automobile or vehicle body. The door comprises a front inclined pillar 10 and a rear vertical pillar 11 transversely joined at the top and bottom thereof in conventional manner and forming a main window opening 12. The outer panel of the door is illustrated at 13, this panel being flanged around the window opening to provide the usual reveal portions 14. The inner metal panel of the door is illustrated at 15, this panel being concealed in practice by an inner trim panel indicated at 16 in Fig. 1. The window reveal at the inner side of the window opening is finished by means of the usual garnish molding 17. As illustrated in Fig. 5 the metal molding 17 is inwardly flanged at 17a and engages a correspondingly flanged portion 14a of the outer panel, thus providing a channel along the side edges and top of the window opening within which is secured a felt covered metal channel strip 18. The channel strip 18 is sloped at the forward edge of the opening in accordance with the inclination of the door and provides the glass runway at the front and rear edge of the opening for the sliding glass panels. The strip extends along the top edge of the opening as shown at 55

18a, see Fig. 1, to provide the header channel for receiving the upper edges of the glass panels when in raised positions. The channel strip 18 has a vertical extension 18b below the window sill which may be secured at its lower edge by a suitable bracket 19 secured to the inner panel 15. The channel strip also has a downward extension 18c at the rear edge of the door for guiding the rear panel during its vertical movement.

10 In the present instance the window opening 12 is controlled by means of two glass panels 20 and 21, the latter being pivoted for swinging movement within the forward portion of the opening. The glass 21 carries a marginal channel shaped metal binding strip 22 which, in the embodiment of Fig. 1, extends continuously around the edges of the glass pane. The glass 21 in turn is supported within a skeleton metal frame 23 shaped to conform to the contour of the forward portion of the window opening, this frame terminating at its lower edge in a depending sheet metal apron 23a. The apron is stamped at its upper horizontal edge to provide a flange 23b spot welded to the lower side of the frame 23, see Fig. 7. The frame 23 around three sides of the glass panel 21 is of general channel shape closed along its outer face and adapted to travel within the glass runway 18. The frame 23 is pressed around its inside to provide dove tail grooves 24 within which are anchored weather strips 25 and 26 of suitable material, such as rubber, shaped to cooperate with the edges of the glass panel 21, when closed, so as to provide a relatively tight joint. The rear vertical side of the frame 23 comprises a channel bar 123 opening rearwardly to receive a felt lined channel member 27 providing a vertical runway for the forward edge of the glass panel 20, this panel having a channel shaped binding strip 28 secured to the marginal edges of the glass.

45 The glass panel 21 is pivoted at its upper edge within the frame 23 by means of a stud 29 secured to the framing 22 and fitting within a socket 30 carried by the frame 23. At its lower edge the panel at 21 is pivotally mounted in the frame 23 by means of a stud 31, see Fig. 7, secured at its upper end to the metal framing 22. The stud or pivot 31 has a bearing within an aperture in the reveal portion 14 of the outer body panel, and carried by the lower end thereof is a pinion 32 having teeth 33 meshing with the teeth 34 of a sliding rack bar 35. The hub of the pinion 32 has a bearing within a plate or bracket 36 which extends transversely through an opening in the apron 23a and is flanged at 37 to embrace one edge of the rack bar 35. The plate or bracket 36 is provided with upwardly projecting tongues struck up from the metal thereof and bolted at 36a to the apron 23a, see Fig. 6. 50 The bottom of the pinion 32 rests upon a plate 39 flanged at its outer edge and riveted at 38 to the bracket 36. The rivets 38 also hold the outer flanged edge of a leaf spring 40, the forward flanged edge of which underlies and engages the bottom face of the rack bar 35 and yieldingly holds the same in position within the flanged edge 37 of the bracket and in mesh with the pinion teeth. 55

60 The rear twisted end of the rack bar 35 is pivoted at 41 to a plate 42 which is offset outwardly and pivoted at 43 to a bracket 44 adjustably secured to the inner panel 15. The lower offset portion of plate 42 is spot welded to a plate or bar 45 and forms therewith an oscillatable two 65 arm bell crank lever. It will be noted that the

70 apron 23a is provided with a two-way slot or guideway comprising, as shown particularly in Fig. 3, a horizontal portion 46 and an upwardly extending radius portion 47. The arm 45 of the bell crank lever is in turn provided with a straight normally horizontal slot or guideway portion 48 corresponding in length to the slot portion 46 and terminating in a downwardly inclined angular portion 49.

75 As best seen in Fig. 1, the member or plate 42, 10 as shown, is provided with an upper offset latch projection or portion 42a. When the parts are in the positions in which they are shown in this figure, the projection or latch 42a engages a stud or stop 44a carried by the adjustable plate or bracket 44 to prevent further movement of the plate 42 toward the left about its pivot 43. Thus, the glass panel 21 is prevented from being swung outwardly beyond a predetermined point, namely beyond its position of Fig. 1. The stop and latch 20 means herein shown for limiting or blocking the outward swinging movement of the glass panel 21, is illustrated, merely by way of example, and it is to be understood that other suitable means may be employed for this purpose. For example, 25 if desired, a stop may be positioned at a predetermined point in the path of movement of a button or stud 60 carried by the long arm 58b of a bell crank lever 58, hereinafter referred to.

30 The glass carrying frame 23 including the 30 apron 23a is shifted vertically into open and closed positions and the pivoted panel 21 is swung horizontally within the window opening by successive movements through the medium of a single regulator mechanism. In the present 35 instance there is illustrated a suitable regulator for accomplishing these operations. The regulator comprises a supporting plate 50 secured to the inner panel of the door and carrying a gear sector 51 pivoted thereto at 51a. Meshing with 40 the sector 51 is a pinion 52 which may be rotated by means of a crank arm 53 on the inside of the door. Fixed to the pivot 51a of the gear sector is a swinging arm 54 to the outer end of which is pivoted at 55 a link 56 which in turn is pivoted 45 at 57 to the short arm 58a of a bell crank lever 58 pivoted at 59 to the supporting plate 50. The long arm 58b of the bell crank carries at its outer end a stud 60 which carries a yieldingly mounted collar 60a held in position against the flanges 50 of the plate 45 by means of a spring 61, see Fig. 8. The stud 60 is installed so as to travel simultaneously in the slots 46 and 47 of the apron and in the slots 48, 49 of the plate 45. By turning the crank 53 of the regulator mechanism to 55 operate the gearing, the bell crank 58 will be turned so as to swing the long arm 58b of the mechanism from the position of Fig. 2 to the position of Fig. 3 and vice versa. It will be seen that the glass panel will be shifted vertically 60 during the travel of the stud 60 in the corresponding guideway or slot portions 46 and 48, Fig. 2 illustrating the lower limit of vertical movement of the glass panel and Fig. 3 illustrating the upper limit when the glass panel is in 65 closed position, the pivoted glass 21 being held in the plane of the panel and the window opening during this time. Thus, by turning the crank 53 in one direction the glass panel may be raised to its full closed position during the travel of 70 the stud 60 in the straight horizontal slot portions 46 and 48. After the glass has reached this closed position, as shown in Fig. 3, further turning of the crank in the same direction will cause the stud 60 to travel idly through the arcuate 75

slot 47, this slot or guideway portion being concentric with the arm 58b and hence preventing vertical movement of the panel. During this time the stud 60 will travel into the angular slot 49 in the plate or bar 45 and by cam action will rock the bar, and hence the arm 42 about the pivot 43. This movement of the bell crank 42, 45 will shift the rack bar endwise thereby rotating the pinion 32 and swinging the pivoted 10 glass 21 on its pivots, as illustrated in Fig. 1.

It will thus be seen that the glass panel 21 may be independently swung, relatively to its 15 slideable supporting frame, into various adjusted positions within that part of the main window opening defined by the area forwardly of the vertical partition bar 123. In this manner 20 ventilating openings of varying sizes may be readily provided by a simple operation of the regulator mechanism. However, it will be noted that vertical movement of the glass panel 21 is prevented until the operator 53 is actuated a predetermined amount to swing said panel into full closed position against the weather stripping 25, 26, as shown in Figs. 4 and 5, and in the vertical plane 25 of the sliding frame 23, after which further movement of the operator causes the panel to be lowered into the body of the door between the inner and outer body panels. Hence, by a continuous turning action of the regulator handle 30 in one direction the glass panel can be raised into its closed position shown in Fig. 3 and then swung about its vertical axis, as shown in Fig. 1, to provide a ventilating opening.

In the present preferred embodiment of the 35 invention, as applied to an automobile door, the main window opening is, for all practical purposes, divided by the partition bar 123 into two openings which are separately closed by means of the glass panels 20 and 21. Where the 40 invention is applied to the rear quarter window opening it may be desirable to construct the pivoted glass panel 21 so as to close the entire opening, thus omitting the sliding panel 20. In the present instance the depending apron 23a of the 45 sliding frame 23 is flanged along its forward vertical edge below the window sill to provide a channel or U-shaped edge portion 62 adapted to be guided within the glass runway 18b, see Fig. 6. The opposite vertical edge of the apron 23a is pressed to provide reverse bends 63 and 64 50 terminating in a flanged edge 65 which is guided vertically in an under-cut slot or recess formed between a channel bar 66 secured to the inner panel and a spacer strip 67 secured thereto by screws, see Fig. 6. The channel strip 27, below the 55 window sill, is spot welded to the inwardly bent edge 63 of the apron.

Fastened to the lower edge of the window glass 20 is a horizontal channel strip 68 to which is 60 secured a depending apron 69 the forward edge of which is pressed to provide a channel shaped portion 70 adapted to slide within the runway 27 carried by the apron 23a, see Figs. 3 and 6. The edge of the apron 69 is reversely bent at 71 and 65 terminates in a flange 72 extending oppositely to the guide flange 65 and slideably vertically within a corresponding under-cut guideway or slot formed between the members 66 and 67, as shown in Fig. 6. From this construction it will 70 be seen that the vertical guide 66, 67 carried by the inner panel framing of the door provides a common guiding means for adjacent edges of the sliding glass panels, the other vertical edges of said panels being guided vertically by the outer 75 runways 18b and 18c. In the present example

the forward vertical edge of the glass 20 and apron 69 is confined within and guided by the channel shaped runway 27 carried by the forward glass panel. If desired, however, the construction may be readily reversed and the runway 27 together with the vertical partition bar 123 may be secured to the rear panel and slide vertically therewith.

Any suitable regulator mechanism may be employed for shifting the glass panel 20 vertically 10 within its guides. In the present instance the apron 69 is provided with horizontal slots 73 within which travel buttons or studs 74 secured to the outer ends of crossed swinging arms 75. These arms are secured to a pair of meshing gears 76 15 which in turn are operated in any suitable manner through reduction gearing generally indicated at 77 from an operating handle or crank 78.

Referring to the regulator mechanism for the vertically slideable window frame 23 it will be 20 noted that the throw or vertical arc of travel of the long arm 58b of the bell crank is materially greater than the arc of travel of the short arm 58a. Hence, a relatively great range of vertical movement of the window is possible as a result 25 of this leverage arrangement. Moreover, the action of the oscillatable arm 54 and link 58 is such as to impart a relatively faster vertical movement of the window near the lower limit of its travel than near its upper limit of travel. 30

Referring now particularly to Figs. 9 to 12 inclusive of the drawings, we have shown therein a modified form of the invention. In this form, the guide means for the adjacent edges of the glass panels is carried by the rear glass panel. The 35 door comprises a front inclined pillar 110 and a rear vertical pillar 111 transversely joined at the top and bottom thereof in conventional manner and forming a main window opening 112. The outer panel of the door is shown at 113, this panel 40 being flanged around the window opening to provide the usual reveal portions 114. The door has an inner metal panel 115. The window reveal at the inner side of the window opening is finished by means of the usual garnish molding 117. The 45 molding 117 is inwardly flanged at 117a and together with the flanged portion 114a of the outer panel, engages a felt covered metal channel strip or member 118. This channel strip provides the glass runway at the front and rear edge of the 50 opening 112 for the sliding rear and front glass panels 120 and 121, respectively. The front glass panel 121 which is mounted for swinging as well as sliding movement, is provided at three sides with a marginal channel-shaped metal binding strip 122. The glass 121 in turn is supported within a skeleton metal frame 123 shaped to conform to the contour of the forward portion of the window opening. The frame terminates at its lower edge in a sheet metal apron 123a. The metal frame 123 is pressed around its inside to provide dovetail grooves 124 within which is anchored a weather strip 125 formed of suitable material, such as rubber, shaped to cooperate with the frame 122 of the glass panel 121 when closed, 55 so as to provide a relatively tight joint. The swinging glass panel 121 is pivoted at its upper edge within the frame 123 by means of a stud 140, and at its lower edge the panel is pivotally mounted by a stud 141.

The rear glass panel 120 carries a metallic guide frame member 128 provided with an inner flange 128a and an outer flange 128b, these flanges being shaped to support and grip therebetween a weather strip 126 of rubber or other suitable material 75

upon which the rear edge of the swinging glass panel 121 engages to form a tight joint. The metal frame for the window panel 120 terminates at its lower edge in a depending sheet metal apron 169. It is, of course, desirable to guide the adjacent edges of the aprons 123a and 169 when the window panels are raised or lowered and for this purpose we have adopted the construction best shown in Fig. 12. Referring to this figure, a channel-shaped member or bracket 130 is secured to the inside panel 118 by bolts or studs 130a. Fastened to the inner face of the member 130 is a guide plate 131 having curved side edges to receive the beads 123b and 169a of the apron members 123a and 169, respectively. A spring retainer plate 132 engages the beads and together with a binder plate 133 and a series of rivets or the like 134, holds the beads against the guide surfaces to provide a uniform sliding contact. It will be understood, of course, that the aprons 123a and 169 and their bead portions slide independently and relatively to the guide member when the window panels are raised or lowered. In order to avoid duplication in the drawings we have not shown in Figs. 9 to 12 inclusive the operating mechanism for the glass panels, but it is understood that the mechanism for this purpose which is shown in the preceding figures of the drawings is embodied in the embodiment of the invention illustrated in Figs. 9 to 12 inclusive.

We claim:

1. In a vehicle body having a window opening, a pair of window glass panels slideable vertically into and out of position within a window well, one of said panels comprising a skeleton frame and a glass panel pivoted within the frame on a vertical axis located intermediate the front and rear edges of the panel, mechanism for swinging said glass when the frame is elevated and including means for sliding the entire frame and glass vertically, and a common vertical guide fixed to the body and located wholly within said window well for independently guiding adjacent vertical edges of said panels during sliding movement thereof.
2. In a vehicle body having a window opening, a pair of window glass panels slideable vertically and independently into and out of position within a window well, the forward panel of said pair being capable of swinging movement when in raised position, guide means at the outer edges of said panels, movable guide means located at the joint of said panels carried by the rear panel and engageable with but movable independently of said swinging panel when the rear panel moves into said well, and separate guide means fixed within the window well in line with said movable

guide means to cooperate therewith to guide and maintain the rear panel in a predetermined vertical position during its movement into and out of said window well.

3. In a vehicle body having a window opening, 5 a pair of window glass panels slideable vertically and independently into and out of position within a window well, the forward panel of said pair being capable of swinging movement when in raised position, guide means at the outer edges 10 of said panels, movable guide means located at the joint of said panels carried by the rear panel and engageable with but movable independently of said swinging panel when the rear panel moves into said well, separate guide means 15 fixed within the window well in line with said movable guide means to cooperate therewith to guide and maintain the rear panel in a predetermined vertical position during its movement into and out of said window well, and independent 20 regulator mechanism for operating each of said panels.

4. In a window regulator mechanism for use in a vehicle door having a window opening and a pair of glass panels cooperable to close the opening, the front panel being mounted to swing horizontally and to slide in an up and down direction and the rear panel being mounted to slide in an up and down direction; a regulator including a swinging arm, a retainer member 30 secured to the lower edge of the sliding panel and connected to said arm, an upright guide member adapted to be mounted in the well of the door beneath the front edge portion of the sliding panel, said guide member having a longitudinal guideway and said retainer member having a transverse extension provided with means 35 slideable in said guideway.

5. In a window regulator mechanism for use in a vehicle door having a window opening and 40 a pair of glass panels cooperable to close the opening, the front panel being mounted to swing horizontally and to slide in an up and down direction and the rear panel being mounted to slide in an up and down direction; a regulator including a swinging arm, a retainer member 45 secured to the lower edge of the sliding panel and connected to said arm, an upright guide member adapted to be mounted in the well of the door beneath the front edge portion of the sliding panel, said guide member having a longitudinal guideway and said retainer member having a transverse extension provided with means 50 slideable in said guideway, and said front panel also having means slideable in said guideway.

MILLARD H. TONCRAY.
EARL H. PICKETT.
